United States Patent Office.

CHARLES E. SIMMONS AND HOMER COOK, OF WAUKEGAN, ILLINOIS.

Letters Patent No. 71,654, dated December 3, 1867.

IMPROVED BED-BOTTOM.

The Schedule referred to in these Letters Patent and making part of the same.

TO ALL WHOM IT MAY CONCERN:

Be it known that we, CHARLES E. SIMMONS and HOMER COOK, both of Waukegan, in the county of Lake, and State of Illinois, have invented new and useful Improvements in "Bed-Bottoms;" and we do hereby declare that the following is a full and exact description thereof, reference being had to the accompanying drawings, making part of this specification, in which—

Figure 1 represents longitudinal side elevations of the bed-bottom,

Figure 2 cross side elevation of the same, and

Figure 3 plan of the plate C and hinges of braces.

The nature of our invention consists in placing two or more pairs of braces between the upper frame, provided with canvas, and supported by ordinary spiral or coil springs, and the lower frame on which said springs rest, said braces being hinged to the upper frame at the top, and secured to the round plates that are attached to the lower frame, and partially revolve on a pivot at the bottom, in such a manner that, when pressure is produced on the canvased frame, said braces yield, owing to the partial pivoting of said plates, keeping the said upper frame in proper place, and preventing its lateral motion.

To enable others skilled in the art to make and use our invention, we will proceed to describe its construction and operation.

A is the lower frame and B the upper frame. C C are plates pinned to the frame A, and revolving around their centres on a pivot. D D and D' D' are the cross-braces, and F F are the longitudinal braces, having their top hinged to the upper frame, and their foot hinged to the plates f f, secured to the plates C C, at the same distance from their pivots. E E are coiled springs.

The operation consists in this, that, when the upper frame is pressed down, the braces partially turn the plates C C, thus yielding under the pressure, keeping at the same time the upper frame in proper position, and preventing its lateral motion under the said pressure.

What we claim as our invention, and desire to secure by Letters Patent, is—

The combination of braces D D D' D' and F F, hinged to the upper frame B and to the plates f f, with the pivoting plates C C, arranged and operating as described.
